BOILER TUBE CLEANER

Louis N. Wheelock, North Amherst, Mass.,
assignor to Boiler Equipment Trust, North
Amherst, Mass., a trust association of Massa-
chusetts

Application August 3, 1933, Serial No. 683,455

4 Claims. (Cl. 122—391)

This invention relates to boiler tube cleaners of the general class in which a series of nozzles are used to direct jets of steam, or other fluid under pressure, into the fire tubes of a boiler for the purpose of blowing out the soot or other accumulation therein, and in which said nozzles are movable back and forth to traverse the ends of the entire series of tubes of the boiler.

One object of the invention is to provide an improved tube cleaning means of this general type by which the time required for cleaning the boiler may be materially reduced, characterized by the use of a plurality rather than a single series of nozzles, each series traversing a different group of fire tubes of the boiler.

Another object of the invention is to provide a tube cleaning means having as rigidly connected parts of the movable unit thereof, two laterally spaced manifold pipes, each carrying a series of nozzles axially spaced thereon and each depending from a point above the uppermost row of fire tubes of the boiler to the lowermost row thereof, said pipes being spaced so that when either one thereof is aligned with an outer vertical row of fire tubes the other is aligned with another vertical row of fire tubes which is substantially centrally located, whereby on moving said unit through a distance approximately equal to half the distance between the two outer vertical rows of fire tubes, said nozzles may traverse the open ends of all the fire tubes.

Another object is to provide in a tube cleaner of the type just described, lower end portions, one for each manifold pipe, which are bent inwardly and disposed in downwardly converging relation, each such end portion being so bent as to clear the water column connection of the boiler and the inwardly curving wall of the smoke box when its manifold pipe lies in its outermost extreme position.

Another object of the invention is to provide in a cleaner of the general class described and not necessarily only in the particular type described, a novel spacing of the outer ends of the nozzles from the open ends of the fire tubes into which the nozzles are adapted to inject steam or other fluid under pressure, characterized in that such ends of the nozzles are spaced from the open ends of the fire tubes by a distance greater than the internal diameter of such tubes and not greater than one and one-half times such diameter. By such spacing the optimum results, insofar as the cleaning effect is concerned, are obtained, having in mind not only the volume of air en-

trained by the steam jets but also the velocity thereof.

A further object of the invention is the provision of a reciprocable tube cleaner hung from a support and operated by mechanism, both of which are located very close to the outer wall of the smoke box in a zone of relatively low temperature and also as far as possible out of the path of the hot gases rising in the smoke box.

Another object of the invention is to provide a tube cleaner which is free from flexible pipe joints and other relatively movable parts likely to warp and cause binding when subjected to the heat prevailing in the smoke box.

A further object is to provide a tube cleaner of simplified and improved construction which is relatively inexpensive to manufacture in that there are comparatively few parts requiring machining and careful fitting, and which is better adapted to operate satisfactorily over a long period of service because of the elimination of parts which may warp and cause binding when subjected to the heat of the fire box.

Other objects will appear as the detailed description proceeds and will be pointed out in the appended claims.

The invention will be disclosed for illustrative purposes in connection with the accompanying drawings, in which:

Fig. 1 is an end elevational view of a boiler, part of the outer wall of the smoke box being broken away to reveal the tubes and tube sheet and tube cleaner of this invention;

Fig. 2 is a fragmentary sectional plan view thereof taken on the line 2—2 of Fig. 1;

Fig. 3 is a fragmentary sectional elevational view taken on the line 3—3 of Fig. 1;

Fig. 4 is an enlarged fragmentary sectional view of one of the bearings for the feed screw of the tube cleaner; and

Figs. 5 to 14 inclusive are diagrammatical views showing a number of standard arrangements of tubes and showing diagrammatically the manner in which my invention can readily be adapted to meet the needs of each such arrangement.

In Figs. 1 to 3 of these drawings, I have shown by way of illustrative example, one standard form of fire tube boiler and the manner in which my invention may be applied thereto. The invention is equally applicable to other forms of fire tube boilers, as I have attempted to show in part and more or less diagrammatically in Figs. 5 to 14, inclusive, and it is in fact readily applicable to any standard form of fire tube boiler now known to me.

Referring first to Figs. 1 to 3 inclusive, the boiler illustrated includes a shell 15, a tube sheet 16, fire tubes 17 and smoke box 18, the outer wall of which is marked 19 and is usually provided 5 with a suitable door such as 20. A feed water connection is indicated at 21, and 22 is a pipe communicating with the water space of the boiler and extending from the tube sheet 16 to and through the wall 19 for connection to the water 10 column (not shown) of the boiler.

The tube cleaner of this invention includes two sets of nozzles 23 and 23', each arranged approximately in vertical series and designed to blow steam into the open ends of the tubes 17. The 15 nozzles 23 and 23' project from manifolds or pipes 24 and 24' which are substantially vertically disposed except for bent lower ends 25 and 25', the lower extremities of which are closed. The upper 20 ends of the pipes 24 and 24' are connected by horizontal pipes 26 and 26' which extend horizontally away from tube sheet 16 toward the wall 19 and which, near this wall, are connected to opposite ends of a horizontally and transversely disposed pipe 27. Pipe 27 has a central inlet 28 connected by a flexible hose 29 to a steam supply pipe 30, which extends outside the shell 15 and is there provided with a suitable control valve 31. The pipe sections 24, 25, 26, 27 and 28 25 are preferably welded together but in any event 30 they are connected to form one rigid unit to which steam or other suitable fluid under pressure is supplied, and by which such fluid is distributed to the several nozzles of the two series described.

35 This rigid fluid conducting and distributing unit is mounted to move back and forth in a substantially horizontal path disposed at right angles to the axes of the tubes 17 for the purpose of causing the nozzles of one set to traverse the open ends of half the tubes 17 and the nozzles of the other set to traverse the open ends of the remaining tubes, so that all thereof are subjected to the action of jets of steam which issue from the nozzles during each stroke in the reciprocation 40 of said unit. For this purpose ears 32 and 33 are suitably fixed, as for example by welding, to the section 21 one near each end thereof. The ear 32 constitutes a nut and is interiorly threaded to fit a feed screw 34. The other ear is slidably 45 mounted on a shaft 35 which is mounted in alignment with screw 34 but need not necessarily turn. Near the outer wall 19 of the smoke box a suitable support, such as an angle iron 36, extends horizontally across the smoke box 50 near the upper part thereof and is suitably fixed as by the brackets 37 to such wall. The vertical leg of angle iron 36 has fixed thereto two bearings 38 and 39. The rod 35 is supported at its ends in said bearings, being suitably fixed, as by the set screws 40, thereto. As shown in Fig. 4, the bearing 39 not only receives an end of rod 35 but also rotatably receives the inner and unthreaded end portion of the feed screw 34. A pin 41, passing through this bearing 39, separates the parts 34 and 35 and forms a thrust bearing for the feed screw 34.

70 The feed screw has an outer unthreaded end portion which extends outwardly through shell 15 and is rotatably supported in a bearing 42, fixed to a bracket 43, secured to shell 15. A collar 44 fixed to said portion, cooperates with one end of bearing 42 to prevent outward axial movement of the feed screw, inner axial movement being prevented by pin 41. Fixed to the outer end of the feed screw is a pulley 45 or any other suitable

means for turning screw 34 first in one and then in the other direction. Ordinarily, a chain 46 is looped over pulley 45 and serves as a suitable means for turning the screw,—such chain extending downwardly far enough so that it may be conveniently pulled by the operator.

5 It will be clear that the rigid distributor unit may be moved back and forth in a straight line by rotating shaft 34 first in one and then in the other direction. The unit is limited in its travel 10 by the abutment of one or the other of the ears 32 and 33 with the bearing 39. The unit, supported as thus described, can swing about the axis of shafts 34 and 35. To hold the unit so that pipe sections 24 and 24' lie substantially 15 vertical, a cross bar 47 extends across the smoke box, near the lower part thereof, and is suitably fixed at its ends thereto. The pipes 24 and 24' 20 slidably engage this bar, the weight of the distributor unit tending to maintain the engagement as does also the reaction of the steam jets issuing from nozzles 23 and 23'.

25 It is to be noted that the distributor unit is slidably supported by means of the simplest character, viz., the ears 32 and 33, from which it is suspended with freedom to swing, and the bar 47 which limits its outward swinging movement. The engagement of these ears 32 and 33 with the members 34 and 35, respectively, is a loose one. That is, the parts are purposely engaged with 30 what is usually termed a sloppy fit, so that binding of the parts under heat is avoided and so that even should the members 34 and 35 warp, the device will still operate. The distributor, being free to swing away from bar 47, is unlikely to 35 bind as it might if it were mounted on a carriage riding on tracks. There are few machining operations required and these are of the simplest character. The bearings 38 and 39 and the ear 33 simply require drilling while the ear 32 40 requires drilling and tapping. Aside from the feed screw 34, there are no parts which are expensive to form,—the shaft 35 being a piece of cold rolled steel which does not need to be machined. The bearings are, or may be, secured to 45 the support 36 by welding and the ears 32 and 33 are secured to the pipe section 21 in a similar manner. The several pipe sections are preferably secured by welding. The entire device may be manufactured at low cost.

50 It is to be noted that the distributor unit is slidably supported and operated by means located closely adjacent the front wall 19 of the smoke box. The shaft 35 and the feed screw 34 are located very close to the wall 19. There are several advantages to this location. First, the parts are located in a zone of relatively low temperature, being removed as far as is feasible from the tube sheet 16. The temperature adjacent wall 19 is at least 100 degrees cooler than that adjacent the tube sheet 16. Consequently, with the 55 relatively movable parts located in the coolest available zone, there is much less liability of any binding of the parts due to the effects of heat, as for example because of warping of the screw 60 34 or shaft 35. Second, the relatively movable parts are removed from the direct path of the hot gases which issue from tubes 17 and pass upwardly through the smoke box 18 to the outlet in the upper end thereof. This again tends to 65 reduce trouble caused by exposure of the parts to heat and, in addition, it minimizes the sooting up of the parts. Third, it enables the distributor unit to be mounted in place in the smoke box without necessitating any change in the location 70 75

of the feed water pipe 21. As will be seen from Fig. 3, there is not room for supporting the unit by means located directly above the upper ends of the manifolds 24 and 24'. Any support placed there would interfere with pipe 21 and necessitate the labor and expense of taking down such pipe and relocating it.

The spacing of the nozzles 23' from tubes 17, as shown herein, is important in that it materially enhances the efficiency of the cleaning operation. Cleaning of the tubes is effected by the wiping action of the gases forced therethrough and not by the direct action of the steam jets from the nozzles. The volume of the gases entrained by these jets and the velocity of such gases are most important factors insofar as the efficiency of the cleaning operation is concerned. Experiments show that the greatest volume of gases is entrained by the jet issuing from a nozzle of any given characteristics and under any given pressure, by spacing the tip of the nozzle from the open end of the fire tube with which it is alined, by an axial distance equal in length to the internal diameter of the tube. An increase in this spacing will cause a diminution in the volume of the entrained gases but, up to a certain point at least, such increase will result in an increase in the velocity of the gases. By experiment, I have found that as said spacing is increased there is a point where the optimum results are obtained,—that is the gain by an increase in velocity more than offsets the loss by diminished volume of the gases. To secure such optimum results, the tips of the nozzles should be spaced from the open ends of the fire tubes by a distance which is greater than the internal diameter of the fire tubes and no greater than one and one-half times such diameter.

The operation of the invention should be largely obvious from the foregoing description. When the fire tubes of the boiler are to be cleaned, the operator opens valve 31, admitting steam to the distributor unit including the manifold pipes 24 and 24'. Steam issues in jets from the nozzles 23 and 23' into the open ends of the two vertical rows of fire tubes which are at that time alined therewith. The tubes are usually cleaned while the boiler is in operation, and this may be done without any drop in pressure in the boiler because the gases, entrained by the steam jets and blown into two vertical rows of tubes for cleaning the same, are derived from the smoke box and hence are drawn through other rows of tubes, which are not then being cleaned, from the fire box. Thus, any loss due to temporary inactivity of two rows of tubes is compensated for by the increased velocity of the gases drawn from the fire box through the other tubes. The operator, having turned on the steam as described, pulls on chain 46 and in this or any other suitable way causes the feed screw 34 to rotate, thus advancing the manifold pipes to the right, as viewed in Fig. 1. In this way, the two series of nozzles are moved successively into alinement with the several vertical rows of tubes. The unit may be reciprocated as many times as is necessary to secure the desired cleaning action, after which valve 31 is closed.

It will be appreciated that the cleaning operation may be effected in half the time ordinarily consumed. Usually, there is only one manifold pipe with a single set of nozzles. Here, there are two working at the same time and the time is cut in two. Also, the operator does not have to do as much work, as the distributor unit has to be

moved only half the usual distance. So also a feed screw of half the usual length can be employed. This makes possible the convenient assembly of the parts from within the smoke box 18 while door 20 is open. The short feed screw 34 and the short shaft 35 will readily enter said box through said door. The shaft 35 may be first put in place in its bearings 38 and 39. Then with the distributor unit in its extreme right hand position, the feed screw may be pushed out through the hole in the wall of the smoke box until its inner end can be threaded into nut 32 and finally into bearing 39. A long feed screw, such as has been heretofore employed, could not be assembled in as convenient a manner.

It is obvious that other pipes, similar to 24 and 24', may be used between these two to still further expedite the cleaning operation, if desired. Ordinarily, however, the two herein shown suffice.

With all usual arrangements of fire tubes, there are less tubes in the outer vertical rows than the inner rows. The manifold tube must of necessity be as long as the longest vertical row. However, if made truly vertical and of such length, it would strike the shell of the boiler and oftentimes also the water column connection 22, when in its extreme position in which its nozzles line up with the fire tubes 17 of an outer row. It has been proposed to cure this difficulty by having the lower end of the manifold pipe pivotally mounted so that it can yield when it strikes such wall or such connection. This means a swing joint which is not desirable in zones of high temperature. I overcome the difficulty by the use of two manifold pipes, the lower ends of which are bent inwardly, as shown, in downwardly converging relation. The part 25 of pipe 24, when the latter is in its extreme left hand position with its nozzles alined with the outer row of tubes 17, will clear the water column connection 22 and one of the nozzles will aline with the lower tube in the next adjacent row. As the manifold is moved to the right, nozzles in the part 25 will successively aline with pairs of tubes 17, one tube of each such pair being in one row and the other in the next adjacent row and below the first tube. With the use of a bent end, such as 25, which is rigidly fixed to the manifold pipe, two such pipes are necessary, as will be obvious.

I have found that the best angle for the part 25 is 25 degrees, as shown herein, although the practical range available varies from perhaps a minimum of about 22 degrees to a maximum of about 33 degrees. With the lower end 25 bent at 25 degrees to the vertical pipe 24, a cleaner constructed as described, can be adapted to any usual fire tube boiler with which I am familiar. For example, the described arrangement will work with any of the standard layouts shown in Figs. 5 to 14 inclusive. These figures are copies of standard tube sheet layouts taken from a manual on boiler making. The manifolds 24 and 25 have been indicated conventionally by a single line. These figures do not show all the standard layouts but they do show enough of them to prove the point that the particular angle is suited to meet a wide range of conditions. It is a fact that the same angle will work with other layouts of tubes and with all standard layouts with which I am familiar.

The invention thus provides a tube cleaner of greatly simplified yet improved construction which is relatively inexpensive to manufacture

and yet extremely effective and reliable in operation.

The invention has been disclosed herein, in an embodiment at present preferred, for illustrative purposes, but the scope of the invention is defined by the appended claims rather than by the foregoing description.

What I claim is:

1. The combination in a boiler, with the smoke box including its outer wall, the tube sheet which forms the inner wall thereof, and the fire tubes which open at one end into said box; of a support located closely adjacent said outer wall, a reciprocating unit including a part slidably mounted on said support and extending therefrom toward said tube sheet and a pipe portion which extends from the inner end of said part downwardly in parallel and closely adjacent relation with said tube sheet, means to supply fluid under pressure to said pipe portion, nozzles on said pipe portion adapted to successively align with rows of said tubes as said unit is moved along said support and through which fluid under pressure is ejected into the open ends of said fire tubes, and means for moving said unit back and forth along said support.
2. The combination in a boiler with the smoke box including its outer wall, the tube sheet which forms the inner wall thereof, and the fire tubes which open at one end into said box; of a support located closely adjacent said outer wall, a reciprocating unit including a part slidably mounted and pivotally hung on said support and extending therefrom toward said tube sheet and a pipe portion which extends from the inner end of said part downwardly in parallel and closely adjacent relation with said tube sheet, means to supply fluid under pressure to said pipe portion, nozzles on said pipe portion adapted to successively align with rows of said tubes as said unit is moved along said support and through which fluid under pressure is ejected into the open ends of said fire tubes, means for moving said unit back and forth along said support, and a cross bar extending transversely of the smoke box at a substantially lower level than said support to restrain pivotal

movement of said unit relative to said support in a direction away from the tube sheet.

3. A boiler tube cleaner, comprising, a pair of manifold pipes each equipped with nozzles and disposed in laterally spaced and parallel relation, a pipe rigidly interconnecting said manifold pipes and having an inlet for fluid under pressure, a support adapted to be fixed in the smoke box of a boiler and to extend transversely across the same, a pair of bearings fixed to said support one near 10 one end and one near the center thereof, a rod having its ends mounted in said bearings, an ear on the second named pipe near one end thereof mounted to slide on said rod between said bearings, a nut fixed to the second named pipe near the 15 other end thereof, a feed screw threaded through said nut and extending from the other end of said support along the same in axial alignment with said rod, said feed screw having its inner end received in the centrally located bearing, and a 20 bearing for supporting the feed screw near its outer end from a wall of the smoke box.

4. A boiler tube cleaner, comprising, a pair of manifold pipes each equipped with nozzles and disposed in laterally spaced and parallel relation, 25 a pipe rigidly interconnecting said manifold pipes and having an inlet for fluid under pressure, a support adapted to be fixed in the smoke box of a boiler and to extend transversely across the same, a pair of bearings fixed to said support one near 30 one end and one near the center thereof, a rod having its ends mounted in said bearings, an ear on the second named pipe near one end thereof mounted to slide on said rod between said bearings, a nut fixed to the second named pipe near 35 the other end thereof, a feed screw threaded through said nut and extending from the other end of said support along the same in axial alignment with said rod, said feed screw having its inner end rotatably received in the centrally located bearing, and a combined supporting and 40 thrust bearing for the outer end of the feed screw, said last named bearing fixed to a wall of the smoke box and outside the latter.
